UNITED STATES PATENT OFFICE.

JOHN SEYS, OF GRAND RAPIDS, MICHIGAN.

DESIGN FOR A STEP PLATE.

Application filed May 7, 1923. Serial No. 6,088. Term of patent 3½ years.

To all whom it may concern:

Be it known that I, JOHN SEYS, a citizen of the United States, residing at Grand Rapids, in the county of Kent and State of Michigan, have invented a new, original, and ornamental Design for Step Plates, of which the following is a specification, reference being had to the accompanying drawing, forming part of this specification, in which drawing—

Figure 1 is a top plan view of a step plate, showing my new design;

Figure 2 is a transverse sectional view of the same taken on line 2—2 of Figure 1; and

Figure 3 is a view in perspective of the same reduced in size.

I claim:

The ornamental design for a step plate, substantially as shown.

In witness whereof, I have hereunto set my hand at Grand Rapids, Michigan, this 4th day of May, 1923.

JOHN SEYS.
